(Cl. D56—9)

To all whom it may concern:

Be it known that I, Jack Barofsky, a citizen of the United States, residing at Los Angeles, in the county of Los Angeles and State of California, have invented a new, original, and ornamental Design for a Casing for a Piano or Similar Article, of which the following is a specification, reference being had to the accompanying drawings, forming part thereof.

Figure 1 is a front perspective view of a casing for a piano or similar article, showing my new design.

Figure 2 is a front elevational view thereof.

Figure 3 is a fragmentary front perspective view of the top front portion of the article as it appears as a blended unit with the body of the article, the illuminated portions and the music rack appearing in a horizontal disclosure.

Figure 4 is a fragmentary front perspective view of the top front portion of the article disclosing the opening of the music rack and the appearance of the illuminated portions in a vertical position as shown in Figs. 1, 2 and 5.

Figure 5 is a side elevational view thereof.

The side opposite that shown in the drawings is the same as the side illustrated.

The back is plain.

The dominant features of my design are shown in solid lines in the drawings.

I claim:

The ornamental design for a casing for a piano or similar article, as shown and described.
